(57) **CLAIM**

The ornamental design for a video borescope, as shown and described.

DESCRIPTION

FIG. 1 is an isometric view of a video borescope showing our new design;

FIG. 2 is a right view of the video borescope of FIG. 1;

FIG. 3 is a left view of the video borescope of FIG. 1;

FIG. 4 is a bottom view of the video borescope of FIG. 1;

FIG. 5 is a top view of the video borescope of FIG. 1;

FIG. 6 is a front view of the video borescope of FIG. 1; and,

FIG. 7 is a back view of the video borescope of FIG. 1.

The broken lines shown in the drawings represent portions of the video borescope that form no part of the claimed design.
